[57] CLAIM

The ornamental design for a reflector for combination stop-tail, turn and backup light, as shown and described.

DESCRIPTION

FIG. 1 is a perspective view of a reflector for combination stop-tail turn and backup light showing my new design;

FIG. 2 is a front elevation view thereof;

FIG. 3 is a side elevational view thereof, the reflector appearing the same when viewed from the opposite side; and,

FIG. 4 is a bottom view thereof, the reflector appearing the same when viewed from the top.

The appearance of my new design as seen from the rear forms no part of the claimed design.
